UNITED STATES PATENT OFFICE.

GEORGE CATHCART SMITH, OF CLAPHAM, LONDON, ENGLAND.

SASH-CORD HOLDER.

No. 873,623.

Specification of Letters Patent.

Patented Dec. 10, 1907.

Application filed August 2, 1907. Serial No. 386,773.

To all whom it may concern:

Be it known that GEORGE CATHCART SMITH, a subject of the King of Great Britain, residing at 514 Wandsworth road, Clapham, London, England, has invented certain new and useful Improvements in Sash-Cord Holders, of which the following is a specification.

The object of my invention is to construct a sash cord holder for hanging windows, so that the sash stile can be easily and readily prepared for attachment of the sash cord, no nails or screws are required for attachment of the sash cord, and a broken sash cord can be readily removed, and a new one attached without it being necessary to remove the sash from the frame as is now the case.

My invention will be readily understood from the following description aided by the accompanying drawings in which:

Figure 1. is a side sectional elevation of sufficient of a window sash to illustrate my cord holder, which is also shown in sectional elevation. Fig. 2. is an edge view of the window sash corresponding to Fig. 1. Fig. 3 is a plan view and Fig. 4. a side elevation of the cord holder. Fig. 5. is a section of one side member of the sash.

For the purpose of my invention, I form my sash cord holder of metal in the form of a cylindrical hollow case, see Figs. 3 and 4, having one side A flat and the other cut away to form an opening B to receive the knot C of the sash cord D.

The base E of the holder is flat and provided with a hole F so as to be readily removable from the sash stile G, as will be hereafter explained.

The top H is angled or beveled, and is provided with a hole I through which the cord D is passed, as will be seen in Fig. 1.

The sash stile G is provided with a groove or channel J, along its entire length, and the part where the holder is positioned is in alinement with the groove J and situate at the bottom of the sash stile and is drilled out, the end of the hole being angled to conform to the top H of the holder, so as to insure the holder gripping the sash stile and preventing the cord pulling the holder out sidewise, and damaging the thin edge of the

sash stile in either side of the flat portion A of the holder.

In fitting a new sash cord, all that is necessary is to lift the sash and prop it up with a piece of wood, then by a tool inserted in the hole F removing the holder and pulling the remainder of the cord D through the groove J, now remove the parting bead between the upper and lower sashes, and the pocket piece in the stile of frame, remove the weight and untie or cut away the cord attached thereto, then take the new cord, pass it through the pulley, and secure it to the weight in the ordinary way, then draw up the weight and secure it against the pulley to get the length of cord which will be three inches longer than the length from pulley to the sill of sash frame. Next pass the cord down through groove J, attach it to the cord holder as shown, insert holder in its proper place, replace pocket piece, and parting bead and the operation is complete.

What I claim as my invention and desire to secure by Letters Patent is:

1. A device for attaching sash cords to sashes, comprising a hollow casing adapted to be inserted into a sash frame, the top of the casing being beveled and provided with a reduced opening for the passage of the sash cord, a side of the casing being provided with a relatively large opening to admit the knot of the sash cord to the casing, and the bottom of the casing being provided with a contracted opening to adapt it to receive a removing tool.

2. A device for attaching sash cords to sashes, comprising a hollow casing of substantially cylindrical form, one side of the casing being flattened to provide a stile engaging surface, and provided at its opposite side with an enlarged opening to admit the knot of the sash cord to the casing, the top of the casing being beveled downwardly toward the flat side thereof and provided with a reduced opening to permit the passage of the sash cord.

3. In a device of the character described, the combination with a sash frame provided with a vertical bore, the upper end of which is beveled in a direction downwardly and outwardly towards the stile-engaging surface, of a casing removably fitted into the

said bore having a knot-receiving opening in one side, and having a beveled top to coöperate with the correspondingly beveled portion of the bore, the top being provided with an opening to receive the sash cord, and the bottom of the casing being accessible from the bottom of the sash and provided with an opening adapted to receive a removing tool.

In testimony whereof I have hereunto set my hand in presence of two subscribing wit- 10
nesses.

GEORGE CATHCART SMITH.
